UNITED STATES PATENT OFFICE.

HENRY A. ARMSTRONG, OF BROOKLYN, NEW YORK, ASSIGNOR TO MERGENTHALER LINOTYPE COMPANY, A CORPORATION OF NEW YORK.

TYPOGRAPHICAL MACHINE.

1,092,813.

Specification of Letters Patent.

Patented Apr. 7, 1914.

Application filed July 12, 1913. Serial No. 778,667.

To all whom it may concern:

Be it known that I, HENRY A. ARMSTRONG, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to 15 form a slug or linotype against the matrices which produce the type characters thereon, and the matrices thereafter returned through a distributing mechanism to the magazine from which they started.

20 More particularly, it relates to the devices whereby the matrices are transferred to the assembler in the course of composition.

In linotype machines of this kind, the matrices when released from the magazine are 25 delivered to a moving endless belt, from which they pass in front of a rotating star wheel by which they are advanced and compacted in the assembler; and at the side of the star wheel is arranged a cover-plate 30 which serves to guide the edges of the matrices and insure their correct delivery. It occasionally occurs that matrices become clogged in proximity to the star wheel and behind the cover, which necessitates the dis- 35 placement of the latter in order to permit the operator to clear the parts. To facilitate this operation, it is also desirable to arrest the rotation of the star wheel, and this has ordinarily been accomplished by its 40 manual disconnection from the actuating devices.

45 It is a specific purpose of my improvement to provide means whereby the movement of the cover itself from and to operative position disconnects and connects the star wheel

and its operating mechanism, and as this same mechanism is employed for the purpose of actuating the assembler belt, it follows that the latter also is simultaneously arrested and restarted.

55 In the accompanying drawings, I have shown my invention in preferred form and by way of example, and as applied to a linotype machine, but many changes and variations may be made therein, and in its mode 60 of application, which will still be comprised within its spirit. Thus for instance, it may be adapted to other forms of typographical machines, such as typesetters, typecasters, and the like, or that is to say, machines 65 which handle type or dies instead of matrices. Or again, the same principle may be applied in other forms, so as to effect the arrest of moving assembling devices, such as the star wheel or assembler belt, by suitable connections, when any adjustable part 70 is moved from its operative position. Generally speaking, I desire it to be understood that I do not limit myself to any specific form or embodiment, except in so far as 75 such limitations are specified in the claims.

In the accompanying drawings: Figure 1 is a front view, partly broken away, of a portion of a linotype machine, having my invention applied thereto; Fig. 2 is a de- 80 tached view, on an enlarged scale and partly broken away, of my specific improvements; Fig. 3 is a sectional view on the line 3—3 of Fig. 2; and Fig. 4 is a sectional view on the line 4—4 of Fig. 3.

85 The matrices are released from the magazine A by the manipulation of the keys A' and are delivered to the assembler belt B, and by it in turn in front of the rotating star wheel C, by which they are advanced 90 and compacted in the assembler D, in conjunction with the spacers which are released from the magazine E by the manipulation of the space key E', all in the usual manner and as illustrated in the previously- 95 mentioned Mergenthaler patent. The actuating means for the belt B and star wheel C comprise the rotating shaft G and connec- tions therefrom to the countershaft J', which carries one of the pulleys B' of the 100

belt B, and also the pinion K which connects through the chain of gearing K', K² with the star wheel C.

As previously set forth, a cover or plate F is located at the side of the star wheel C to guide the matrices as they pass from the belt B and to prevent their accidental displacement. It sometimes occurs that the matrices clog or pile up behind the plate F, and the latter is therefore movably mounted, as upon the rock shaft L, to permit its displacement from operative position and to give the operator access to the parts. In such circumstances, it is also desirable to arrest the rotation of the star wheel. This has ordinarily been accomplished by a distinct manual operation, and it is a principal purpose of my invention to effect it automatically by connections from the cover F, in such manner that when the latter is moved from or to operative position, the actuating engagement is correspondingly broken or restored.

By way of illustration, I have shown frictional connecting means between the shaft G and the countershaft J', these means comprising a disk J on the countershaft J', so located and arranged that it engages at its periphery with the side of a disk H, splined upon the shaft G and pressed normally into operative position by a spring H' mounted within its hub and bearing against a collar H² upon the shaft. The rock shaft L, whereon the cover F is mounted, is provided with an arm L', which is connected by a link L² to one end of the shift lever M, pivoted at M' and forked at its farther end M² and engaging the groove H³ in the hub of the disk H.

The normal condition of the parts is that indicated in Fig. 1, wherein the cover F is in operative position, and at which time the disk H is held in frictional contact with the disk J, this effecting the rotation of the countershaft J' and the actuation of the belt B and star wheel C through the connections previously described. When the cover F is displaced, in order to give access to clogged matrices or the like, as shown in Fig. 2, the consequent rocking movement of the shaft L, through the arm L', the link L² and lever M, shifts the disk H rearwardly against the force of the spring H', and thus breaks the actuating connection between the shafts G and J', which results in the arrest of the star wheel C and assembler belt B. When the cover F is returned to operative position, this actuating connection is restored.

As previously stated, I have shown my invention only in preferred form and by way of example, and in a special mode of adaptation, but obviously many modifications and alterations therein will suggest

themselves to those skilled in the art, without departure from its scope. 65

Having thus described my invention, its construction and mode of operation, what I claim and desire to secure by Letters Patent of the United States, is as follows: 70

1. In a typographical machine, the combination of the rotating star wheel C, the cover-plate F movable to and from operative position, and means whereby the movement of the cover-plate to inoperative position arrests the star wheel. 75

2. In a typographical machine, the combination of the star wheel C, actuating means therefor, the cover-plate F movable to and from operative position, and means whereby the movement of the cover-plate to and from operative position connects and disconnects the star wheel and its actuating means. 80

3. In a typographical machine, the combination of the traveling assembler belt B, the cover-plate F movable to and from operative position, and means whereby the movement of the cover-plate to inoperative position arrests the travel of the belt. 85

4. In a typographical machine, the combination of the assembler belt B, actuating means therefor, the cover-plate F movable to and from operative position, and means whereby the movement of the cover-plate to and from operative position connects and disconnects the belt and its actuating means. 90

5. In a typographical machine, the combination of the traveling assembler belt B, the rotating star wheel C, the cover-plate F movable to and from operative position, and means whereby the movement of the cover-plate to inoperative position arrests the assembler belt and star wheel. 100

6. In a typographical machine, the combination of the assembler belt B, the star wheel C, common actuating means therefor, the cover-plate F movable to and from operative position, and means whereby the movement of the cover-plate to operative and inoperative position connects and disconnects the assembler belt and star wheel with and from the common actuating means. 110

7. In a typographical machine, the combination of a moving assembling device, a cover-plate movable to and from operative position, and means whereby the movement of the cover-plate to inoperative position arrests the assembling device. 115

8. In a typographical machine, the combination of an assembling device, actuating means therefor, a cover-plate movable to and from operative position, and means whereby the movement of the cover-plate to operative and inoperative position effects the connection and disconnection of the assembling device and its actuating means. 125

9. In a typographical machine, assem-

bling mechanism comprising a plurality of constituent matrix-engaging elements, one of which is movable at will out of operative relation to the others, a matrix conveying belt, and actuating means therefor, in combination with means whereby the movement of the aforesaid assembling element out of its operative relation automati-

cally breaks the connection between the belt and its actuating means.

10

In testimony whereof I have affixed my signature in presence of two witnesses.

HENRY A. ARMSTRONG.
